DOUBLE INLET BLOWER WHEEL

Addison W. Evans, Torrington, Conn., assignor
to The Torrington Manufacturing Co., Torrington,
Conn., a corporation of Connecticut

Application April 8, 1942, Serial No. 438,108

5 Claims. (Cl. 230—134)

This invention relates to improvements in double inlet blower wheels, and more particularly to blower wheels of double inlet types characterized by a body of unitary construction, as distinguished from those in which the blade elements are individually formed and assembled to one or more shaft-mounting spiders, ring or plate members.

The present invention has as a general object, a reduction of number of parts and simplification of assembly of a double inlet centrifugal blower wheel.

More particularly stated with respect to presently preferred embodiments, the invention is objectively embodied in a blower wheel of a type in which the blade-forming body of the wheel is or may be constructed of a single strip or sheet of material capable of being readily formed and shaped, and in which the single body element is characterized by, say, a pair of rows of peripheral blade elements and apertures, and in which wheel the body is intermediately mounted or supported for rotation about an axial element such as a shaft.

Yet another object of the invention is attained in an improved assembly of a one-piece blade-forming body for a centrifugal wheel, to a center plate or spider, through connection of the peripheral portion of the spider to an intermediate portion of the body.

An additional and important object of the invention is found in improved means for assembling a double-row, bladed rotor body to a central mounting spider therefor, and which securely anchors the body against any radial displacement either inwardly or outwardly with respect to the periphery of the spider, and as well positions the bladed body against any longitudinal or axial displacement with respect to the central mounting plate or spider.

Another object may be stated as attained in a construction for the purposes and with the advantages noted, in which the elements of the wheel are themselves formed into interlocking assembled securement to produce an unusually rigid wheel structure, and without necessarily requiring the use of rivets, screws, bolts, welding or other extraneous fastening expedients.

Numerous other objects and advantages of the invention will appear from the following detailed description of certain preferred embodiments, particularly when considered in connection with the accompanying drawing, in which:

Fig. 1 is a side elevational view, partly broken away to show the interior construction 55

of a double end blower wheel characterized by a unitary body portion and exemplifying the present invention; Fig. 2 is a vertical elevation, partly in section as taken along staggered planes as indicated by line 2—2 of Fig. 1; Fig. 3 is an exploded view, partly in section, showing peripheral portions of each of the major elements of the wheel in their relation just prior to assembly; Fig. 4 is an exploded view similar to Fig. 3, but showing the same elements after assembly; Fig. 5 is a fragmentary sectional view in a plane through the axis of the wheel but showing a slightly modified form of beaded or crimped connection between the periphery of a central spider, and an intermediate portion of the body, and Fig. 6 is a view similar to Fig. 5 but showing a still further modified form of structure for assembly of wheel spider and body.

Referring now by characters of reference to the drawing, the example disclosed includes a body-forming portion of substantially cylindrical shape, indicated generally at 10. The body element 10 is initially comprised of a strip of sheet metal (not shown) which is first punched to provide a series of parallel spaced lines of incision of the metal, the metal between such lines being turned or formed out of the then flat or cylindrical plane of the body sheet to constitute a series of parallel blades 11. It will appear from the drawing that the body 10 is imperforate in a zone just beyond the ends of the blades, there remaining on each lateral margin of the body strip, a portion 12, which in the wheel lies substantially in the cylindrical plane which roughly defines the shape of the finished body. The details of construction of the body strip and the formation thereof to cylindrical shape, do not per se constitute any feature of present improvements, and hence for a more complete description thereof reference is directed to Letters Patent #2,231,062 of the present applicant, issued February 11, 1941, and entitled "Centrifugal blowers."

The present improvements relate principally to centrifugal blower wheels of those types in which a body of unitary or one-piece type, is assembled in a central or intermediate zone thereof to a shaft-mounted spider which may be in the form of a center plate. Wheels of this broad category find a considerable demand in the trade under conditions wherein it is desirable to admit air to the interior of the wheel, from both ends thereof; wheels of this type being sometimes referred to as of double inlet, single plate type.

As thus embodied and as will appear from the

drawing, the bladed body 10 is accordingly formed with two rows of blades 11 and with one or two of the cylindrically planar imperforate margins 12 at the inside ends of and between the two rows of blades as will readily appear from Figs. 3 and 4, and which zone is utilized, as will hereinafter be more fully described, for securingment of the unitary body to the center plate.

The plate or spider shown, has been so developed that when formed in any usual gauge of sheet metal, it exhibits a high resistance to deformation, and hence serves admirably to retain the true cylindrical shape and initial balance of the wheel. The mounting plate presently illustrated is the subject of and claimed in Letters Patent #2,272,695 issued February 10, 1942, to this applicant, and entitled "Centrifugal blower wheel structure." It may be noted principally for present completeness, that this assembly includes a hub 13 provided with a set screw 14 and shaft aperture 15. The hub 13 is provided with a partly conical plate-seating face 16, against which bears a correspondingly shaped portion 17 of the center plate. Extending inwardly from the portion 17 of the plate is a flange 18 which is closely embraced by a spunover or upset lip portion 19 constituting initially an extension of the hub 13. The engagement of portions 19 and 18 is such that the plate is securely positioned in a plane transverse to the axis of hub rotation, and firmly held against any axial or angular displacement. By preference also the center plate is provided, for rigidity, with a plurality (shown as four) of rib-like protuberances 25. These are tapered in section as appears from Fig. 2, and extend outwardly to, and merge into an annular truss and seat-forming portion 26. The portion 26 is so shaped that its outer surface 27 is arcuate or cylindrical, and in assembly lies closely parallel to the inner portions 12 of the bladed body 10.

Beyond the portions 26 and 27 in the periphery of the center plate, is an upstanding flange 30, the outer portion of which is doubled or folded over on itself as shown at 31, but the portion 31 being by preference of lesser depth than portion 30. This formation results in what is, in effect, a laterally undercut groove 32, this groove being annular in form and serving a purpose herein-after better appearing.

Referring further to the construction of the unitary body 10 of the wheel, either before or after formation of the body strip or sheet to its cylindrical shape, the outside lateral margins 12 thereof, are outturned to form flanges 40. These serve, as will appear, to receive in crimped embracing engagement, an end ring generally indicated at 41, located at each of the open ends of the wheel. The end rings are also provided with outstanding flanges 42 which, in assembly, are turned inwardly, thence downwardly into overlying and closely embracing relation to the flanges 40, and in such manner that the inturned ends 43 serve as abutments to prevent any outward radial displacement of the margins of the body, in coaction of course with the outer extremities of the margins 40 in engagement with the bight of each folded portion of flanges 42. The present illustration is of a small diameter double inlet center plate wheel in which it is not necessary that the rings 41 have any direct shaft support. In larger types of wheel it may of course be desirable, as is contemplated, to utilize a form of ring in each of the end zones of the wheel, which is provided with a hub and spoke elements (not shown), it being understood

that the present invention does not exclude the possibility of end mounting in addition to a central shaft mounting.

An important feature of the present improvement is found in providing for a rigid self-securement of the body to the periphery of the center plate or spider, without necessarily requiring any incisions or weakening of the intermediate zone of the body-forming strip for this purpose. As shown, the central imperforate area indicated by the inner portions 12 is, either while the body is in strip form or after its cylindrical shaping, formed by rolling or any other suitable known means, to result in an outwardly extending annular portion 44, in the nature of a rounded, exteriorly presented bead, the shaping of which results in an inwardly open channel or groove 45 which is initially of a width to receive and fully to accommodate the flange portions 30 and 31, over their full radial depth, and to permit at least one of the portions 12 to seat firmly upon the arcuate surface 27 of the plate. From this it appears that the annular seat or groove 45 coacts with the flange 30-31 and particularly with the undercut seat or groove 32, to enable the body to be deformed in these zones into firm and permanent assembly with the plate.

A slightly modified form of securingment expedient for attachment of the body to the center plate, is shown by Fig. 5, wherein the intermediate planar zones of the wheel are indicated at 50, and the portion 50 provided with an outwardly extending annular bead or the like 51, resulting in groove 52. In this form, the folded portions 53 and 54 are more rounded in form but there still results beneath the portion 54, the laterally presented groove corresponding generally to the groove 32 (Figs. 3 and 4).

A further minor modification is illustrated by Fig. 6, wherein the central cylindrical planar body portion 60 is somewhat more deeply grooved to form an annular bead 61 receiving the folded flange elements 62 and 63. In this modification it will be observed that portion 62 is displaced somewhat in a direction laterally of the major plane of the plate 64 so that there result two laterally presented shouldered portions similar to the undercut groove 32, and corresponding generally in purpose thereto. The manner of assembly of the bladed body to the spider in each of the modifications is sufficiently similar to that characterizing the assembly of parts shown by Figs. 3 and 4, that a separate description thereof is not regarded as necessary.

Referring now briefly to the manner of bringing into operative relation the several major elements of the principal showing, it will be understood that the bladed body, having been cylindrically shaped with its ends suitably positioned as by a jig or special tool for this purpose (not shown), the end rings 41 are positioned in the open ends of the body so that the outer end margins 12 of the body seat firmly upon the arcuate seating portions thereon on the rings 41, and with the flanges 40 and 42 in close parallel adjacence. Following this the now extending portions of flanges 42 are brought inwardly, then downwardly into close parallel overlying relation to the flanges 40, from which it will appear that the inturned parts of the end ring serve distinctly as truss members in supporting and maintaining the truly circular aspect of the outer margins of the body.

With the periphery of the center plate formed as shown by Fig. 3, the center plate and body may

be brought into assembly relation with the flange 30 and portion 31 seated and bottoming in the groove 45. Following this, by suitable rolling equipment or otherwise as desired, the bead 44 in or near its zones of juncture with the adjacent body portion 12, is crimped to bring these portions into the laterally presented annular groove such as 32. It will now clearly appear that the parts are assembled in such manner that any inward radial deformation of the body is impossible because of its firm support by the arcuate seat 21 which in turn is truss-supported by the underlying elements of the annular conformity 26 of the plate. Any outward displacement of the center part of the body is impossible because of the interlocking engagement of the metal of the bead 44 in the groove 32.

The manner of assembly of the wheel to the shaft, as by extension of the shaft through hub opening 15 and threading up of set screw 14 will appear as obvious.

It will have appeared that the structure as described fully attains each and all of the several objects expressed and implied from more detailed description; it will also appear that numerous changes may be made in the structure specifically described; details of the latter having been included for completeness and instruction, but without any intent thereby to limit the scope of the claims hereunto appended.

I claim as my invention:

1. A centrifugal blower wheel including an integral, bladed sheet metal body of substantially cylindrical form, a center plate provided with substantially wide, arcuate truss-supported shoulder portions just inwardly of its periphery, and formed just outwardly of said shoulder portions, with arcuately grooved seating portions in which the groove is laterally presented, the metal of the body intermediate its length, having a doubled portion extending into and substantially filling said grooved portions, and radially inwardly thereof, lying closely adjacent to said shoulder portions.

2. A centrifugal blower wheel including a bladed body formed of a strip of metal shaped to constitute the blades and end margins, a mounting plate having a portion inwardly of but near its periphery, formed to provide a wide, cylindrical body seat, an annular truss portion supporting said body seat, and a doubled flange portion projecting radially outwardly of said seat, the body being provided in a central zone, with a combined stiffening and securement groove extended away from the normal cylindrical plane of the adjacent portions of the body, said groove

being assembled into gripping relation with the peripheral flange of the spider, and with the center zone of the body metal supported by said cylindrical seat of the spider.

3. The elements and combination as recited by claim 2, further characterized in that the blower wheel is entirely open at both ends, and the body supported solely in an intermediate zone by crimping of said groove portion to said flange portion of the spider.

4. In a centrifugal blower wheel, a body of integral construction formed to provide two spaced rows of blades and open for air inlet purposes at both of its ends, a center plate adapted to receive a shaft for rotatably supporting the wheel thereon, the center plate being provided with a truss-supported, substantially cylindrical body-seating surface slightly inwardly of the plate periphery, the body being crimped in an intermediate zone to a portion of the plate periphery adjacent said cylindrical seating portion, and the plate being formed to provide a plurality of radial protuberances in the nature of spoke-like reinforcing portions having their origin close to the shaft-engaging portion of the plate, thence extending outwardly to, and merging into the cylindrical body-seating portion of the plate, the body being crimped into securement with portions of the plate lying just outwardly of said cylindrical seating portion.

5. In a centrifugal blower wheel, a body of integral construction formed to provide two spaced rows of blades and open for air inlet purposes at both of its ends, a center plate adapted to receive a shaft for rotatably supporting the wheel thereon, the center plate being provided with an axially wide groove of substantially C shape in section, the outermost part of which constitutes a cylindrical seat for a cylindrical center portion of the body, the inner portion of the groove constituting an annular truss for supporting the seat, said groove being located slightly inwardly of the plate periphery, the body being crimped in an intermediate zone to a portion of the plate periphery adjacent said cylindrical seat, and the plate being formed to provide a plurality of radial protuberances in the nature of spoke-like reinforcing portions having their origin close to the shaft-engaging portion of the plate, thence extending outwardly to, and merging into the cylindrical body-seating portion of the plate, the body being crimped into securement with portions of the plate lying just outwardly of said cylindrical seating portion.

ADDISON W. EVANS.
